UNITED STATES PATENT OFFICE.

JAMES WILLIAMSON, OF CHICAGO, ILLINOIS, ASSIGNOR TO R. WILLIAMSON & COMPANY, OF CHICAGO, ILLINOIS.

CANDLE FIXTURE.

Application filed July 14, 1922. Serial No. 575,053.

To all whom it may concern:

Be it known that I, JAMES WILLIAMSON, a citizen of the United States, residing at Chicago, in the county of Cook and State 5 of Illinois, have invented certain new and useful Improvements in Candle Fixtures, of which the following is a specification.

This invention relates generally to lighting fixtures and more particularly to any 10 type of candle fixture.

One of the objects of the invention is to simplify and improve the construction of lighting fixtures, to reduce the number of parts, and the cost of manufacture, and to 15 provide a strong and substantial structure which standardizes the sockets and insures the use of the proper socket at all times.

Another object of the invention is to provide a closed cup for the fixture which is 20 ornamental in appearance, substantially dust proof and easily manufactured at comparatively low cost.

It has been customary heretofore to provide candle fixtures with a nozzle and a separate candle stem screw threaded thereon. These stems have been made in different lengths to accommodate electric sockets of 25 different lengths. These separate parts add to the cost of manufacture, increase the liability of the parts to loosen and of the 30 fixture to lose its desired rigidity and enable dealers and others to substitute other stems for the stem which the manufacturer intended to be used on a particular fixture and thereby possibly distorting the shape 35 and configuration and spoiling the appearance of the fixture. The cups heretofore employed have generally been open, presenting an unfinished appearance and consisting 40 of a collector of dust, and they have often been made in a very flimsy and unsubstantial manner and are easily dented and otherwise injured, especially around the open edge thereof.

45 My invention is intended to overcome these deficiencies in the manufacture of candle fixtures and I have found in the practical commercial use of fixtures embodying the invention that they not only possess 50 the structural merits sought for but they also present an attractive and ornamental appearance, which is less likely to be affected by carelessness in handling or installing than has been the case heretofore.

55 In the accompanying drawings I have il-

lustrated the invention in a candle fixture of the wall bracket type and referring thereto

Fig. 1 is a plan view of a double wall bracket, partly in section, embodying the 60 invention;

Fig. 2 is a side view of a portion of a candle fixture, partly in section and illustrating another form of the invention.

Referring to the drawings the tubular arm 65 is extended up through the cup which comprises the bottom member 6 and the top member 6' and which is supported in proper position on the arm by a collar or shoulder 7 secured in place on the arm by 70 any suitable means. The upper end of the arm projects through the top member 6' of the cup and is threaded to receive the threaded nipple 8 of the socket which is designated generally 9. The nipple bears 75 against the top member of the cup which rests upon the shoulder 7 and to properly space the parts of the cup I provide a sleeve 10 which is mounted on the arm within 80 the cup and is arranged with its ends engaging the top and bottom members. The two members forming the cup are provided with eyeleted openings 11-11 to accommodate the pull cord 12 which passes therethrough and is connected to the socket 85 switch. The outer edge of the top member 6' of the cup is provided with a depending flange 13 which is arranged to fit snugly 90 within the outer edge 13' of the lower member 6 to form a dust proof cover and ornamental finish for the lower member 6 and for the cup as a whole.

The sleeve 10 is not only important to space the parts of the cup and to hold them against undue pressure in screwing the 95 socket onto the arm, but it also tends to hold the two members of the cup against relative movement during the assembling of the parts, whereby the openings 11-11 may be maintained in proper alignment. 100 The sleeve also constitutes a reinforcement whereby all the parts of the cup structure are rigidly secured together when the socket is screwed into place on the arm. By extending the arm through the cup to form 105 the stem which has heretofore been made separate from the arm, I avoid the use of a loose part, eliminate the expense of making this part and providing the arm with a nozzle to receive it, and I provide a more 110

rigid and permanent structure. The top member of the cup forms a substantially dust proof cover for the lower member which has heretofore generally been left 5 open, and thereby adds to the attractive appearance of the cup and helps to preserve it against deformation.

While I consider the sleeve a desirable element it is not absolutely essential under 10 all conditions and in Fig. 2 I have shown a fixture without the sleeve and also omitting the pull cord, this fixture being designed for use with a wall switch.

The invention is simple in construction 15 but it relates to an art which has been rather closely worked and its various features are designed to accomplish results which increase the efficiency, improve the appearance and reduce the cost of manufacture of lighting fixtures.

I am aware that the form, construction and proportion of parts may have to be varied from those shown to a more or less extent in adapting the invention to other 20 lighting fixtures and I reserve the right to

make all such changes as fairly fall within the scope of the following claims:

I claim:

1. A lighting fixture comprising a cup having a top member and a bottom member, an arm extending up through both members of the cup, a shoulder on the arm forming a support for the cup, a sleeve on the arm to space apart the top and bottom members of the cup, and a socket secured on the 30 end of the arm against the top member of the cup.

2. A lighting fixture comprising a cup having a top member and a bottom member, an arm extending up through the cup and 40 threaded at its upper end, a shoulder on the arm forming a support for the cup, a spacing sleeve on the arm within the cup, and a socket screwed on the threaded upper end of the arm above the cup and 45 clamping the top member of the cup against the upper end of the sleeve and the bottom of the cup between the lower end of the sleeve and the shoulder on the arm.

JAMES WILLIAMSON.
